UNITED STATES PATENT OFFICE.

JERARD R. MARSICO, OF BROOKLYN, NEW YORK.

HORN-ACTUATING MECHANISM.

1,288,636.

Specification of Letters Patent. Patented Dec. 24, 1918.

Application filed May 20, 1916. Serial No. 98,840.

To all whom it may concern:

Be it known that I, JERARD R. MARSICO, a citizen of the United States, residing at Brooklyn, in the county of Kings and State 5 of New York, have invented new and useful Improvements in Horn-Actuating Mechanism, of which the following is a specification.

My invention relates to horns, signals, 10 alarms, or the like wherein the sound is produced by mechanically disturbing or flexing a resilient diaphragm and among its many features of construction, it includes an adjustable striker mechanism for producing 15 clear and soft sound of high intensity, power and proper pitch.

The present invention resides in mechanism for increasing the velocity and amplitude of the movement of the diaphragm so 20 that the vibrations produced will be of large carrying power and such power being regulatable so that the largeness of the sound and its carrying power may be varied according to the desires of the operator.

25 I have also provided a regulating mechanism for the striker or rotor which will be fully operative for the purpose of compensating for all ordinary losses of efficiency of the striker and anvil with a continued 30 use of the horn.

Among other objects in view, the invention 35 consists of a peculiarly formed anvil or wear piece having an attenuated contacting surface which gradually merges into an enlarged portion of the anvil, the former and the latter being of the same degree of hardness, and the enlarged portion having connection with the diaphragm so that the vibrations will be such that a resulting clear 40 tone will follow. The restricted portion while being of the same degree of hardness as the enlarged portion, is free to yield sufficiently to permit of the desired movement 45 of the striker or rotor relatively of the diaphragm for the purpose specified.

With the above and other objects in view which will appear as the nature of the invention is better understood, the same consists in the improved construction and novel 50 arrangement of parts which will be herein-after more fully described and particularly pointed out in the claim.

In the drawings forming a part of this specification and in which like numerals of

reference indicate similar parts throughout 55 the several views:—

Figure 1 is a side view of the horn with parts in section.

Fig. 2 is a side view of another form of horn showing the application of the invention thereto.

Fig. 3 is a sectional view of the horn shown in Fig. 1 with parts in elevation, the striker and anvil being on an enlarged scale.

Fig. 4 is a section through a portion of 65 the motor.

On reference to Fig. 1 of the drawings it is seen that use is made of a horn A, including a bell B, and a resonator C, a diaphragm D, being interposed between the former and 70 the latter and secured thereto in any suitable well known manner. Said resonator is provided with a tubular depending extension E, provided with a vertical passage F, which is flared and arranged with its restricted end 75 lowermost. The extension is provided at diametrically opposite sides with passages F' which receive screws or equivalent studs G which extend through lugs H, on a motor casing I, the latter containing any suitable 80 well known form of motor which may be influenced by a controlling cord J, having a push button K. The shell of the resonator is connected with a bracket L, having a suitable stand M.

The head piece N, of the motor casing I, is provided with a vertical bushing O, which extends through the flared passage F, in the extension E, of the resonator. The shaft P, of the motor extends through the bushing 90 and it terminates within the resonator as shown in Fig. 1. At this point the shaft supports a striker or rotor 1, held to the shaft by a nut 2. Adjacent to the striker and embracing the bushing O, is a collar 3. Loosely 95 connected with the collar 3 is an adjusting screw 7. The screw passes through a threaded passage 9, in the adjacent wall of the resonator and exteriorly of said wall, the screw is exposed and provided with a kerf 100 10, by means of which it may be manipulated by a suitable tool. In this manner the entire motor is adapted to tilt from the resonator body of the structure in order that the striker may be moved toward or away from 105 the diaphragm for a purpose to be herein-after explained. Jam nuts 11 are mounted upon the screw and one of these nuts is

adapted to be brought into engagement with the resonator wall so as to hold the screw in the desired adjusted position while the other nut may contact with the collar 3. A 5 cotter pin 11^a is passed through the stem at one side of one or both of the nuts.

The striker or rotor 1, is provided with an 10 annular series of parallel arranged relatively shallow depressions or cuts 12, adapted to co-act with fingers 13—13, upon an anvil or wear piece 14. The fingers 13 of the anvil or wear piece are rather attenuated and each is 15 of a restricted diameter toward the striker and in the opposite direction the said fingers merge into the enlarged body portion of the anvil which is passed through the center of the diaphragm D, after having been associated with companion washers 15—15, arranged respectively at the opposite sides 20 of the diaphragm. The anvil may be constructed of steel of the same uniform degree of hardness throughout. In view of the peculiar arrangement of the fingers 13—13, which, as described, are attenuated, it will 25 be observed that the latter are adapted to yield slightly in order that they will accommodate themselves accurately to the various angles of adjustment of the striker 1. It is found that by providing the attenuated 30 fingers 13—13 of the restricted diameter in

the direction of the striker 1, the vibrations which are imparted thereto to contact with the striker, will be very nicely transmitted to the main central body of the anvil to be taken up by the diaphragm with a resultant 35 clear, and amplified or augmented sound.

What is claimed as new is:—

A sound producing device for signals, comprising a motor, an acoustic diaphragm, having a wear piece, a resonator shell supporting said diaphragm, and including an extended portion having a flared passage, a widened end of which is extended into said shell, driving mechanism mounted to tilt from the extension and having a shaft extending through said passage, and a striker located in said shell and secured to said shaft, a bushing carried by the motor, and embracing the shaft, a collar extending around the bushing, and a threaded stem 40 working through the shell and connected with the collar so that on adjustment thereof the motor and said striker will be tilted, as 45 and for the purpose set forth.

In testimony whereof I affix my signature 50 in presence of two witnesses.

JERARD R. MARSICO.
